UNITED STATES PATENT OFFICE

167,689

JEWELRY DISPLAY PACKAGE OR SIMILAR ARTICLE

Julius J. Hommer, Union, N. J.

Application December 26, 1951, Serial No. 17,829

Term of patent 7 years

(Cl. D80—5)

To all whom it may concern:

Be it known that I, Julius J. Hommer, a citizen of the United States, residing in Union, Union County, New Jersey, have invented a new, original, and ornamental Design for a Jewelry Display Package or Similar Article, of which the following is a specification, reference being had to the accompanying drawing, forming a part hereof:

Fig. 1 is a front perspective of my jewelry display package with the cover removed and with the rack pivoted upward;

Fig. 2 is a perspective view of the cover; and

Fig. 3 is a front perspective of the complete jewelry display package showing my new design.

I claim:

The ornamental design for a jewelry display package or similar article, as shown.

JULIUS J. HOMMER.
